RECORDER AND REPRODUCER FOR SPIRAL
PHOTOGRAPHIC DISK SOUND RECORDS

James J. Dilks, Jr., Haddon Heights, N. J.

Application November 3, 1943, Serial No. 508,838

13 Claims. (Cl. 179—100.3)

1

This invention relates to sound recording methods and apparatus, and it has reference more particularly to methods and apparatus for recording sound photographically on sensitized film.

The chief aim of this invention is to enable sound to be recorded with absolute fidelity on photographic film either as a laterally undulating line track, a track of uniform density and varying width, or a track of uniform width and varying density.

The first mentioned variety of sound track is produced as hereinafter more fully disclosed, by moving sensitized film past an opening through which a small surface area of the film is exposed, causing a thin pencil beam of concentrated light to be oscillated laterally in accordance with the sound which is to be recorded, and by causing the beam to impinge upon the moving film surface within the confines of the exposure opening. The second variety of sound track is obtained by causing a restricted beam of slender triangular cross-section to be vibrated laterally in the direction of its cross-section and in the direction of a narrow chink of uniform width through which the surface of the moving film is exposed; and the third variety of sound track is created by employing a narrow recording beam of uniform width and elongate section to be vibrated laterally of a correspondingly shaped chink through which the surface of the moving film is exposed.

Another aim of this invention is to render possible the production of spiral sound tracks characterized as above stated on a sensitized film disk. This latter objective is attained, as hereinafter more fully set forth, by rotating the film disk and by concurrently moving an element which provides the exposure opening, as well as the recording beam, radially of said disk.

In connection with apparatus for making sound records under the above principles, it is a still further aim of this invention to provide means whereby the rotative movement of the film disk is varied compensatively with the changing radius of the sound spiral so that a uniform speed is determined for the disk surface linearly of the spiral.

Another object is to incorporate in sound recording apparatus having the foregoing attributes, means whereby the rate of movement of the exposure aperture and the light beam may be changed relative to the rate of rotation of the film disk to alter the pitch (convolution spacing) of the spiral sound track.

A further object of this invention is to provide indicating means from which the extent to which the recording has progressed at any time during

2

the operative cycle of the apparatus can be ascertained.

Other aims and objects, with attendant advantages, will appear from the following detailed description of the accompanying drawings.

Fig. I is a top plan view of a sound recording apparatus conveniently embodying this invention.

Fig. II is a longitudinal section of the apparatus taken as indicated by the arrows II—II in Fig. I.

Fig. III is a cross-section taken as indicated by the arrows III—III in Fig. I.

Fig. IV is a horizontal section taken as indicated by the arrows IV—IV in Fig. II.

Fig. V is a fragmentary section on a larger scale, taken as indicated by the arrows V—V in Fig. I.

Fig. VI is a fragmentary section, likewise drawn to a larger scale and taken as indicated by the arrows VI—VI in Fig. I.

Fig. VII is a detail section taken as indicated by the arrows VII—VII in Fig. VI.

Fig. VIII is a fragmentary detail section, taken as indicated by the arrows VIII—VIII in Fig. V, showing the drive mechanism of the apparatus.

Fig. IX is a horizontal section of the drive mechanism, taken as indicated by the arrows IX—IX in Fig. VIII.

Fig. X (sheet 5) is a detail section taken as indicated by the arrows X—X in Fig. V and showing the clutch means associated with the drive mechanism.

Fig. XI is a wiring diagram of the apparatus.

Figs. XII, XIII and XIV, are detail views illustrating various types of light beam shaping elements, capable of interchangeable use in the apparatus, for producing the correspondingly different forms of sound wave recordings respectively shown in Figs. XV, XVI and XVII.

Fig. XVIII is a detail section, taken as indicated by the arrows XVIII—XVIII in Fig. I, showing the set-up employed to produce the wave form of sound recording featured in Fig. XV.

Fig. XIX is a fragmentary detail sectional view, taken as indicated at XIX—XIX in Fig. XVIII.

Figs. XX and XXI are views, corresponding to Figs. XVIII and XIX, showing the set-up employed in producing the form of recording featured in Fig. XVI.

Fig. XXII is a vertical section on the plane XXII—XXII in Fig. II.

Fig. XXIII is a fragmentary view, corresponding to a portion of Fig. I, showing an alternative

form of means for indicating the progress of the sound recording; and

Fig. XXIV is a plan view of a film disk having interruptions in its sound track.

As shown in Figs. I and II, the improved sound recording apparatus has a flat rectangular base plate 1 from each corner of which rises a post 2. Mounted on the posts 2 in fixed relation thereto at an elevation well above the base plate 1, is a rectangular frame 3, having a horizontal diaphragm 4 depressed somewhat below its top edge to provide a shallow recess 5. Slidingly engaging the rods 2 above the frame 3 is an upper frame 6 of corresponding configuration having a perimetric flange 7 upstanding from a horizontal web portion 8. To the underside of the frame 6 is secured a gasket 9 of felt or the like, which, when said frame is lowered, is adapted to seal against the top edge of the frame 3. The frames 3 and 6 thus jointly form a shallow light-occluding enclosure for reception of a sensitized film disk D of Celluloid or the like upon which the sound is photographically recorded as later on explained.

For the purpose of raising and lowering the upper or cover frame 6, there is provided means including a horizontal operating shaft 10 (Figs. II and III) with a hand-wheel 11 at one end thereof, said shaft extending longitudinally of the apparatus and being journaled in bearings 12 at the lower ends of brackets 13 secured to, and pendant centrally of, the opposite ends of the frame 3. The brackets 13 also include bearings 15 for the lower ends of vertical shafts 16 with screw threaded portions engaging axially into internally tapped sleeves 17. As shown, the sleeves 17 extend upward through guide openings in the frame 3 and contact with the bottom face of the cover frame 6. At its lower end, each sleeve 17 embodies a polygonal head 18, one side face whereof slidably engages the inner side of the confronting bracket 13 and thus prevents said sleeve from rotating with the coating screw shaft 16. As shown in Fig. II, the screw shafts 16 are driven by the operating shaft 10 through the medium of miter gear-couples respectively designated 19. Accordingly, rotation of the operating shaft 10 in one direction will, through the screw shafts 16 and sleeves 17, be attended by elevation of the cover frame 6 above the frame 3, to the position shown in Fig. III, for convenience in placing and removing the film disk D; while rotation of said operating shaft in the opposite direction will result in lowering said cover frame 6 to the normal position illustrated in Fig. II.

Centrally mounted on the diaphragm 4 of the frame 3 is a plate 20 with an annular recess 21, Fig. V, in its top occupied by a turn-table 22 for the film disk D. The turn-table 22 has an upward axial boss 23 and two upstanding eccentrically-arranged stud projections 24, 25 of different diameters adapted to fit correspondingly-allocated openings 24', 25' in the film disk D, best shown in Fig. XXIV, and thus determine a definite position for said disk. The turn-table 22 also has a depending axial boss 26 which projects through aligned openings respectively in the diaphragm 4 of the frame 3 and in a reinforcing bar 27 extending crosswise of said frame. As shown in Fig. V, the turn-table 22 has a key coupling-connection 28 with the upper end of the shaft 29 of an induction motor which is generally designated 30 and is enclosed in a protective housing 31, the frame 32 of said motor and the housing 31 being firmly secured to the bar 27.

The induction motor 30 is generally of the type 75

ordinarily employed in phonographs, comprising a disk rotor 33 which revolves in the gap between pairs of electromagnets 34, 35, respectively supported at opposite sides of the motor frame 32, see Fig. VIII. The speed of the motor 30 is controlled by a fly-ball governor 36 which is mounted on a shaft 37 and driven by a worm 38 and a worm wheel 39 from the motor shaft 29. As the governor 36 expands, a disk 40 connected to the fly-ball arms 41 reacts upon a finger 42 pivoted at 43 to the motor frame 32, see Fig. IX. Integral with the finger 42 is an arm 45 which has a ball-joint connection 46 with one end of a link 47, see Figs. VIII and IX, whereof the other end is connected to an adjustable crank member 48 secured by a screw 49 to a gear sector 50. The gear sector 50 is fulcrumed on a stud 51 projecting from one side of the motor frame 32 and, as shown in Fig. VIII, meshes with a gear pinion 52 on another shaft 53 which is journaled at one end in said frame and, at the other end, to a bearing bracket 54 secured to the frame 3, see Fig. V. The shaft 53 is axially shiftable outward to an extent limited, through engagement of a collar 55 thereon with the bearing bracket 54, by pull upon a finger knob 56 at its outer end. By means of a helical spring 57 in compression between the pinion 52 and a supplemental bearing plate 58 attached to the motor frame 32, the shaft 53 is normally maintained in the position shown in Figs. V and X, with clutch teeth 59 on said pinion engaged with clutch teeth 60 on the hub of a spur gear 61 on a short tubular-shaft 62 axially aligned with the shaft 53 and journaled in the motor frame 32. The gear wheel 61 in turn meshes with a pinion 63 on another shaft 64 journaled in the motor frame 32, the latter shaft also carrying a worm 65 which is driven by a worm wheel 66 on the motor shaft 29. By the speed-reducing gear connections just described, the sector 50 is slowly moved counterclockwise in Fig. VIII, and through the finger 42 actuated from said sector, the restraint imposed upon the governor 36 is gradually increased with attendant gradual increase in the speed of the motor 30 for a purpose which will be fully explained later on. The movement of the sector 50 is limited in one direction through engagement thereof with a fixed stop 67, see Fig. VIII.

50 The optical equipment of the apparatus is all mounted on a carriage 70 (see Figs. I-III, V and VI) with grooved rollers 71 at the ends of transverse parallel axles 72 engaging vertically spaced pairs of parallel track rods 73 which extend longitudinally of the cover frame 6. The rods 73 have their ends fixed in keepers 73a attached to the perimetric flange 7 of said frame, see Fig. I. The carriage 70 is moved along the rails 73 by means of a screw spindle 74 journaled at its inner end in a bearing 75 centrally of a reinforcing cross bar 76 in the cover frame 6, and at its outer end in the perimetric flange 7 of said frame. Resting by gravity upon the screw spindle 74 is a weighted block 77 in the form of a half-nut with internal threads in engagement with the threads of said spindle. As shown the nut-block 77 is connected to a yoke whereof the side arms 78 are pivoted on one of the roller axles 72 of the carriage 70, so as to be swingable upwardly out of engagement with the screw spindle 74 when desired or required, the block being provided with a knob 79 for convenience in lifting it. As shown in Figs. I and II, the screw spindle 74 carries a miter gear 80 at its inner end which meshes with a similar gear 81 at the upper end

of a short vertical shaft 82. This shaft 82 revolves freely within a sleeve 83 which is axially aligned with the motor shaft 29, and which extends down through a bearing 84 centrally of the cross-bar 76 of the cover frame 6.

Secured to or integrally formed with the sleeve 83, at the bottom, is a disk 85 which has recesses 86, 87 and 88 to respectively receive the upper boss 23 and the upstanding projections 24, 25 of the turn-table 22 so that it may coact with said turn-table as a clamp to hold the film disk D in place upon lowering of the cover frame 6, as shown in Fig. V. Affixed to the short shaft 82 and miter gear 81 is a spur gear 89 which is driven by an intermeshing pinion 90 on a sleeve 91, secured by a set-screw 92 to a vertical countershaft 93. From Fig. V, it will be further noted that the countershaft 93 is journaled at its lower end in the cross-bar 76, and at its upper end in a bridge piece 94 supported at the top of a pair of uprights 95 on said bar. To the countershaft 93 is also secured a spur gear 96 which is in turn driven by an intermeshing pinion 97 at the top end of the sleeve 83 carrying the film clamping plate 85. By this arrangement, it will be apparent that the screw spindle 74 will be actuated from the motor shaft 29 at reduced speed to shift the carriage 70 along its rails 73 during rotation of the film disk D. The purpose of this carriage movement will also be fully explained later.

In order that the speed of the screw spindle 74 relative to the speed of the turn-table 22 may be changed, the sleeve 91 is provided with an additional gear wheel 98 which lies below the plane of another gear 99 on the short shaft 82. By loosening the set-screw 92 and shifting the sleeve 91 upward on the countershaft 93, the gear 98 may be meshed with the gear 99 with attendant unmeshing of the gear pinion 90 from the gear wheel 89. The reason for the two different speeds of the screw spindle 74 will also be set forth later.

The optical equipment hereinbefore mentioned includes a source of light in the form of a high-powered incandescent bulb 100 which is enclosed within a housing 101. As shown in Figs. I and VI, the lamp-housing 101 is supported by a bridge bar 102 which is secured, with capacity for adjustment, to the roller axles 72 of the carriage 70. Adjustable endwise in a lateral tubular boss 103 of the light housing 101 is a barrel 104 fitted with a pair of lenses 105 by which the light emanating from the bulb 100 is condensed and projected into a prism 106 having a mirrored reflecting surface 107. As shown in Fig. VII, the prism 106 is affixed centrally of a supporting plate 108 which is vertically adjustable on screw studs 109 upstanding from the circular base 110 of a sleeve 111 centrally recessed into the carriage 70, the adjustment of the prism being fixable by jam-nuts 112, 113. The light projected into the prism 106 as above explained, is reflected downward into another lens holder 115 telescopically engaged in the sleeve 111 which is fitted with a pair of lenses 116 by which the reflected light is further condensed and concentrated. The inner sleeve component 117 of the holder 115 which directly carries the lenses 116 has laterally projecting ears 118 which are pierced to engage over the screw studs 109, see Fig. VII. Helical springs 119 exert upward pressure upon the ears 118 of the sleeve 111 to keep said ears yieldingly in engagement with adjusting nuts 120 on the screw studs 109. Incorporated with the lens holder 115 is an iris diaphragm conventionally indicated at

121 and which may be adjusted by turning an intermediate knurled sleeve 122 of said holder.

Coaxial with the lens holder 115 is a cylindrical block 123 having a circumferential flange 5 at the top which is recessed into the carriage 70 below the flange 110 of the sleeve 111. As shown the reduced portion of the block 123 extends down through a longitudinal slot 125 in the plate 8 of the cover frame 6 (see Figs. I, VI, XVIII and XIX), and fixed axially within it by a set screw 126, is an inverted, thimble-like plug 127, having a square aperture 128 in its bottom which is rounded and projects slightly below the block 123. As shown in Fig. VI, the bottom of the block 123 is covered with a soft annular facing 129 of felt, velvet or the like, for light occluding engagement upon the upper face of the film disk D. Within the plug 127 is a circular diaphragm 130 having a square orifice 131 10 which is somewhat smaller than the aperture 128 in the block 123 and which defines the width of the sound track made on the film disk D. As shown in Fig. XVIII, the diaphragm 130 is fixed against displacement by a sleeve 134 forced into 15 the plug 127.

25 A pair of overlapping sectoral vanes 135, 136 disposed within a triangular recess 137 in the web 8 prevent entry of light through the slot 125 into the disk film enclosure jointly afforded by 30 the frames 3 and 6, see Figs. I, II, V and VI. As shown in Figs. I and II, the vanes 135, 136 pivot on a stud 138 and are respectively provided with complementally-arranged diagonal-slots 139, 140 through which the pendant portion 35 of the plug 123 on the carriage 70 passes with a snug fit. The vanes 135, 136 also respectively have arcuate slots 141, 142 concentric with the pivot 138 to clear the sleeve 83 with a snug fit. By virtue of this arrangement, it will be 40 seen that as the carriage 70 is shifted along the track rods 73 toward the axis of the film disk D from the position shown in Fig. I, the vanes 135, 136 will be brought into closer eclipse through camming action between the plug 123 and the diagonal slots 139, 140 and thereby effectively guard the slot 125 at all times.

45 The film disk D is kept in firm light-occluding contact with the facing 129 of the plug 127, during the recording, by a presser plate 145 (see Fig. IV) of flexible sheet metal, which, at 50 one end, is secured by a clamp bar 146 to the top of the diaphragm 4 of the frame 3. The free end of the presser plate 145 is covered with padding 147 of felt or velvet to contact the film disk from beneath, see Fig. VI, and said plate 55 is urged upwardly by a pair of spring wedge members 148. As shown, these wedge members 148 are slotted longitudinally as at 149 for passage of the shanks of securing screws 150 engaging into the diaphragm 4 of the frame 3, 60 so as to be adjustable to vary the pressure.

65 Also supported by the carriage 70 is a magnetic modulator 151 which may be of any well known design or make, and which is employed for vibrating a light beam by which the sound recording is effected. As shown in Figs. VI and VII, the modulator 151 is secured to a plate 152 which is apertured to engage over the screw studs 109 hereinbefore referred to, and it is held 70 in position, with capacity for up-or-down adjustment, between pairs of nuts 153, 154 respectively on said studs. Removably attached to the horizontally-vibrating armature 155 of the modulator is a hearing controller in the form of a tongue 156 (Figs. VI, VII and XI) which ex-

tends transversely of and intercepts the shaft of light reflected downward by the prism 107, except for a pencil beam which is permitted to pass through a pin hole (Fig. XII) therein and enter the lens holder 115 on the carriage 70, as shown by the vertical arrow in Fig. VI.

In addition to the induction motor 30, the light bulb 100 and the modulator 151, the electrical equipment used in the apparatus includes a variable transformer 158 (Fig. XI) for controlling the bulb, a microphone 159, a suitable form of amplifier 160 for intensifying the action of the modulator 151, and a "decibel" meter 161 for indicating the intensity or volume of the sound, these elements being all suitably wired together as shown in the diagram and receiving current from a power line 162, 163. At 165 is shown a master switch for starting and at 164 a volume control knob.

At 166 in Figs. I and II, there is shown an indicator comprising a dial 167 at the front of a small housing 168 attached to the perimetric flange 7 of the frame 6 at one side thereof, and a pointer 169 which is secured to a shaft 170 passing axially through said dial. By a train of gears 171, 172 and 173, 174, the pointer shaft 170 is driven from the outer end of the screw spindle 74, the gear ratios being such that the pointer 169 makes a complete circuit of the dial 167 for each complete traverse of the carriage 70. By means of a knob 175, it is possible to re-set the pointer 169 to starting position after each operative cycle of the apparatus. The dial 167 may be graduated to indicate the number of turns made by the turn-table 22 during each recording, or in any other convenient way.

In Fig. XXIII, I have shown an alternative form of gauge means in which a pointer 169a attached to the half-nut 71 overtravels a linear scale 167 secured to the top of the web 8 in the frame 6.

Having described the apparatus for carrying out the improved method of sound recording, the operation thereof is briefly as follows:

Preparatory to starting, a blank film disk D is placed upon the turn-table 22 within the enclosure 3, 6, and the carriage 70 moved to the position shown in Figs. I and II; such movement being accomplished by raising the yoke 78, by the knob 79, to disengage the half-nut 71 from the screw spindle 74, whereupon the carriage 70 is pushed along the track rails 73 until said nut abuts the bearing brackets 75. The switch 165 (Fig. XI) is next closed with the result that the electric motor 30 and the light bulb 100 are brought into action, with attendant closing of the circuit between the microphone 159 and modulator 151 through the amplifier 160, and closing of the circuit or circuits containing the volume meter 161. By operation of the motor 30, the film disk D is slowly turned clockwise, in the direction of the arrow shown in Figs. I and IV, under control of the fly-ball governor 36. Due to its connection with the motor shaft 29, the screw spindle 74 is concurrently rotated slowly with the result that the carriage 70 is moved radially of the film disk D toward the center of the latter; and, as a result thereof, a sharp spiral line track T will be produced on said disk by the pencil light beam projected downwardly through the pin-hole 157 in the tongue 156 and, through the registering aperture 131 of the diaphragm 130, in the plug 127 on the carriage 70. In responding to the action of the microphone 159, the modulator 151 causes the tongue 156 to be vibrated horizontally

as indicated by the double arrow in Fig. XV, so that nodes of varying amplitude are formed in the sound track, as shown in Figs. XV and XIX, corresponding in character to the sound waves impressed upon said microphone. As the recording proceeds, the speed of the turn-table 22 is gradually accelerated in proportion to the decreasing radius of the sound track T by action of the finger 42 (Fig. IX) upon the motor governor 36 in the manner hereinbefore explained, so that the speed of travel of the film disk surface past the aperture 131 in the diaphragm 130 is kept constant with avoidance of any crowding of the undulations in the track which would otherwise result if the speed of the turn-table 22 were uniform. The progress of the recording is shown at all times by the pointer 169 of the indicator 168. A complete circuit of the pointer 169 around the dial 167 indicates that the carriage 70 has reached the end of its inward travel, whereupon the switch 165 (Fig. XI) is opened to bring the apparatus to rest. Finally, the film disk D is removed and a fresh one substituted in its place for the next recording. After each operative cycle, the sector 50 is restored to the starting position, shown in Fig. VIII, by grasping the knob 53 and pulling the shaft 53 outward to disconnect the clutch teeth 59, 60, and then turning said shaft counter-clockwise until the sector again contacts the stop 67.

Having thus described my invention, I claim:

1. Sound recording apparatus comprising a mounting for a sensitized film disk; an element with an opening through which a minute area of the disk is exposed; means for producing a shaft of concentrated light; a recording beam controller with a light-restricting aperture; means responsive to sound vibrations for oscillating the recording beam controller crosswise of the light shaft; and means for rotating the mounting and concurrently moving the element aforesaid, the light producing means, the sound vibration responsive means and the recording beam controlled radially of the disk so that a spiral sound track is produced on the film disk.

2. Sound recording apparatus according to claim 1, including means for gradually varying the rotative movement of the mounting compensatively with changes in the radius of the spiral track to determine a constant speed of the disk surface linearly of said track.

3. Sound recording apparatus comprising a mounting for a sensitized film disk; an element with an opening through which a minute area of the disk is exposed; means for producing a shaft of concentrated light and directing it toward the exposure opening; a recording beam controller with a light-restricting aperture; means responsive to sound vibrations for vibrating the recording beam controller crosswise of the light shaft; a motor for rotating the film disk mounting; means for concurrently moving the element aforesaid, the light producing means, the vibration-responsive means, and the recording beam controller radially of the film disk so as to predetermine production of a spiral sound track on said disk; a governor associated with the motor; and means for automatically controlling the governor compensatively with the changing radius of the spiral track and thereby determine a uniform speed of the disk surface linearly of the spiral sound track.

4. Sound recording apparatus comprising an enclosure; a mounting for a sensitized film disk

within the enclosure; means for rotating the mounting; a carriage confined to horizontal travel above the enclosure radially of the film disk; an element with an exposure opening extending from the carriage down through a slot in the top of the enclosure into contact with the disk; means preventing entry of light into the slot; means on the carriage for producing a shaft of light and directing it toward the exposure opening; a recording beam controller with a light-restricting aperture; means also on the carriage responsive to sound vibrations for oscillating the recording beam controller crosswise of the light shaft; and means for moving the carriage concurrently with rotation of the film disk mounting, so that a spiral sound track is produced on said film by the controlled recording light beam.

5. Sound recording apparatus according to claim 4, wherein the means for rotating the film disk mounting include a motor; and wherein an automatic governor varies the speed of the motor compensatively with change in the radius of the spiral sound track produced on the film disk, to determine a constant speed of the disk surface linearly of said sound track.

6. Sound recording apparatus according to claim 4, wherein the carriage is moved by a screw, and means operatively coordinating said screw with the drive means for the disk mounting.

7. Sound recording apparatus according to claim 4, wherein the means for rotating the film disk mounting includes a motor, to the shaft of which said mounting is secured; wherein the carriage is shifted by a screw spindle; and wherein in the screw spindle is geared to the motor shaft.

8. Sound recording apparatus according to claim 4, wherein the means for rotating the film disk mounting includes a motor to the shaft of which said mounting is secured; wherein the carriage is shifted by a screw spindle; and wherein the screw spindle is driven from the motor shaft by change speed gearing so that the spacing of the convolution of the spiral sound track produced on said disk may be varied.

9. Sound recording apparatus according to claim 4, wherein the carriage is moved by a screw spindle operated from the drive means for the disk mounting; and wherein the coupling connection between the carriage and the screw spindle includes a half-nut, and a supporting-arm for the nut pivotally connected to the carriage, so that said nut can be disengaged from the spindle to permit return of said carriage to starting position, at the termination of an operative cycle of the apparatus.

10. Sound recording apparatus according to claim 4, further characterized by an indicator to show the progress of the recording, and means

operatively coordinating said indicator for movement by the carriage.

11. Sound recording apparatus according to claim 4, wherein the enclosure includes a fixed bottom component and a cover component; lifting means for the cover component include a plurality of vertical screw shafts; internally threaded sleeves hold against rotation with the screws and engage the cover component from below; an operating shaft; and gearing whereby the screw shafts are concurrently rotated by the operating shaft.

12. Sound recording apparatus according to claim 4, wherein the enclosure includes a fixed bottom component and a liftable cover component; the disk mounting is journaled in the bottom component; the carriage and the means for moving it are supported by the cover component; and wherein the carriage moving means includes a plate which is journaled in the cover component, said plate being adapted to bear downwardly upon the film disk and to operatively couple the carriage moving means with the disk mounting.

13. Sound recording apparatus according to claim 4, wherein the enclosure includes a fixed bottom component and a liftable cover component; the disk mounting is journaled in the bottom component and provided with eccentrically arranged studs for engagement in correspondingly-allocated openings in the film disk; the carriage and the means for moving it are supported by the cover component; the carriage moving means includes a plate which is journaled in the cover component, said plate being adapted to bear downwardly on the film disk, and openings in the plate wherein studs on the disk mounting are received to operatively couple the carriage moving means with said mounting.

JAMES J. DILKS, JR.
